UNITED STATES PATENT OFFICE.

LYMAN ARNOLD, OF LYNN, MASSACHUSETTS, ASSIGNOR TO GENERAL ELECTRIC COMPANY,
A CORPORATION OF NEW YORK.

CONSTANT-CURRENT TRANSFORMER.

No. 895,831.

Specification of Letters Patent.

Patented Aug. 11, 1908.

Application filed March 9, 1907. Serial No. 361,442.

To all whom it may concern:

Be it known that I, LYMAN ARNOLD, a citizen of the United States, residing at Lynn, county of Essex, State of Massachusetts, 5 have invented certain new and useful Improvements in Constant-Current Transformers, of which the following is a specification.

My invention relates to constant-current transformers of the type employing relatively movable primary and secondary coils, and its object is to provide a single transformer which is adapted to supply a plurality of independent secondary circuits, and which, when operated from a polyphase supply-circuit, loads all the phases of the supply circuit. To secure these results I provide a plurality of sets of relatively movable primary and secondary coils and a magnetic core which is common to the sets and so arranged that all the magnetic material is effectively utilized for each set, while each set is enabled to operate separately from the others.

My invention will best be understood by 25 reference to the accompanying drawings, where

Figure 1 shows a side elevation of a constant-current transformer arranged in accordance with my invention; Fig. 2 shows a 30 plan view in cross-section on the line 2—2 of Fig. 1; Fig. 3 shows an isometric view of the core; and Fig. 4 is a diagram of the transformer connections when operated from a three-phase supply circuit.

35 In the drawings A represents a magnetic core on which is supported two primary coils B B.

C C represent secondary coils which are 40 movable with respect to the primary coils, and for this purpose are supported by cables D connected to counter-weights E E. Sectors F are provided to give a straight-line 45 vertical movement to the secondary coils. It will be noted that the coil arrangement forms two axially-alined sets of relatively 50 movable primary and secondary coils. The core A has a central portion which passes through all the coils in series, and has two outer legs which form with the central portion a closed magnetic circuit common to all 55 the coils. A third portion a joins the central and outer core portions between the two sets of coils. This arrangement enables each set to utilize effectively all the mag-

netic material of the core, while at the same 55 time, owing to the magnetic member a between the sets, each set is independent of the other in operation.

A transformer as thus constructed may be 60 operated from a single-phase source of supply for supplying two independent secondary circuits, or the transformer may be operated from a three-phase supply-circuit in which case it serves to load all the phases of the supply-circuit. The connections for operation 65 on a three-phase circuit are shown in Fig. 4. In this figure G represents a constant potential three-phase circuit, to which the primary coils B B are connected with the well known T-connection. The secondary coils C C are 70 connected to independent constant-current load-circuits H H. With this connection of the coils all the phases of the supply-circuit are loaded, while constant current is maintained in the load-circuits independently of 75 each other.

What I claim as new, and desire to secure by Letters Patent of the United States, is,—

1. A constant-current transformer comprising a plurality of sets of relatively-movable 80 primary and secondary coils and a common magnetic core for said sets having a magnetic member separating said sets.

2. A constant-current transformer comprising a plurality of axially-alined sets of 85 relatively-movable primary and secondary coils, and a magnetic core having a portion extending through said sets in series, a second portion outside said coils forming with the first portion a closed magnetic circuit common to said sets, and a third portion 90 joining the first and second portions between said sets

3. A constant-current transformer comprising a plurality of sets of relatively-movable 95 primary and secondary coils and a common magnetic core for said sets, and a plurality of independent constant-current circuits supplied from the secondary coils of said transformer.

4. In combination with a polyphase constant potential supply-circuit and a plurality of single-phase constant-current load-circuits, a constant-current transformer comprising a plurality of sets of relatively-movable 105 primary and secondary coils and a common magnetic core for said sets.

5. In combination with a three-phase

100

105

constant-potential supply-circuit, a constant-current transformer comprising a pair of primary coils connected in T to said circuit, a common magnetic core for said coils having a portion separating them, and a pair of secondary coils relatively movable with respect to said primary coils.

In witness whereof, I have hereunto set my hand this fifth day of March, 1907.

LYMAN ARNOLD.
